A. W. JOHNSON.
WIRE CLOTH RACK.
APPLICATION FILED MAR. 17, 1916.

Patented June 5, 1917.

2 SHEETS—SHEET 2.

UNITED STATES PATENT OFFICE.

ANTRUM W. JOHNSON, OF WARRENTON, MISSOURI.

WIRE-CLOTH RACK.

1,229,086.

Specification of Letters Patent.

Patented June 5, 1917.

Application filed March 17, 1916. Serial No. 84,859.

To all whom it may concern:

Be it known that I, ANTRUM W. JOHNSON, a citizen of the United States, residing at Warrenton, in the county of Warren and 5 State of Missouri, have invented certain new and useful Improvements in Wire-Cloth Racks; and I do hereby declare the following to be a full, clear, and exact description of the invention, such as will enable others 10 skilled in the art to which it appertains to make and use the same.

This invention relates to a wire cloth rack and has for its primary object to provide means for accurately measuring wire cloth 15 when unwound from the rack.

An object of this invention is to provide a pair of upwardly and inwardly inclined supporting bars, having a plurality of notches to receive the ends of spindles, which 20 support rolls of wire cloth, whereby various widths of rolls of wire cloth may be accommodated and efficiently supported by the supporting bars.

Another object of this invention is to provide a measuring roller, having a friction roller adjacent thereto, to receive the wire cloth as it is unwound, to measure the wire cloth in desired lengths.

A further object of this invention is to 30 provide means for raising and lowering the measuring and friction rollers to place them in parallel alinement with any one of the rolls of wire cloth which is being unwound.

A further object of this invention is to 35 provide means for locking the measuring and friction rollers in parallel alinement with any one of the rolls of wire cloth.

A still further object of this invention is the provision of a wire cloth rack of the 40 above stated character, which will be simple, durable, and efficient, and which may be manufactured and sold at a comparatively low cost.

With these and other objects in view as 45 will become more apparent as the description proceeds, the invention consists in certain novel features of construction, combination and arrangement of parts as will be hereinafter more fully described and 50 claimed.

For a complete understanding of my invention, reference is to be had to the following description and accompanying drawings, in which:

5 Figure 1 is a front elevation of a wire

cloth rack, constructed in accordance with my invention,

Fig. 2 is a vertical sectional view of the same,

Fig. 3 is a fragmentary longitudinal sectional view, illustrating the manner of journaling the measuring and friction rollers, 60

Fig. 4 is a fragmentary vertical sectional view, taken on the line 4—4 of Fig. 1, and drawn on an enlarged scale, 65

Fig. 5 is a plan view of a pinion for moving the measuring and friction rollers upwardly and downwardly,

Fig. 6 is a fragmentary longitudinal sectional view taken on the line 5—5 of Fig. 1, and 70

Fig. 7 is a perspective view of a collar for locking the measuring roller in a desired position.

Referring in detail to the drawings, the 75 numeral 1 indicates a pair of transversely extending feet, having upwardly and inwardly extending supporting bars 2 secured thereto, which are provided with a plurality of upwardly directed notches 3, to receive 80 spindles 4, having rolls of wire cloth 5 thereon. Any number of spindles 4 of various lengths may be supported upon the supporting bars 2 for supporting rolls of wire cloth 85 of various widths. The upper ends of the supporting bars 2 are secured together by a cross beam 6, having its ends projecting to points beyond.

A pair of vertically extending rack bars 7 are secured to the feet 1 and to the ends 90 of the cross beam 6 and provided with rack teeth thereon. A pair of shoes 9 are slidably mounted upon the rack bars 7 and apertured to receive a shaft 10, having collars 11 thereon to prevent lateral movement 95 thereof. Secured to the shaft 10 is a friction roller 12 that rotates with the shaft 10 and which will be hereinafter more fully described. The shoes 9 are provided with openings 13 to receive a shaft 15. The shaft 100 15 has secured thereon a measuring roller 16 which is 12 inches in circumference and positioned in parallel alinement with the friction roller 12. Journaled upon the shaft 15 are pinions 17 and positioned within the 105 shoes 9 and provided with oppositely disposed slots 18. The pinions 17 are in mesh with the rack teeth 8 and adapted to move upwardly and downwardly thereon, causing the shoes 9 to move upwardly and down- 110

wardly on the rack bars 7, carrying the friction roller 12 and the measuring roller 16 therewith.

Keyed to the shaft 15 are collars 19, having arms 20 formed thereon and are adapted to extend through the openings 13 in the shoes 9 and engage the slots 18 in the pinions 17, when the shaft 15 is moved laterally on the rack bars 7 to lock the pinions 17 to the shaft 15. Secured to one end of the shaft 15 is a crank handle 21 and by rotating the shaft 15 by the crank handle 21, the pinions 17 are caused to travel upwardly or downwardly on the rack bars 7 depending in which direction the shaft 15 is rotated to move the friction roller 12 and measuring roller 13 in parallel alinement with any one of the rolls of wire cloth 5.

To lock the friction roller 12 and measuring roller 16 in parallel alinement with any one of the desired rolls of wire cloth 5, the shaft 15 is provided with collars 22, having arms 22', similar to the arms 20. The collars are apertured to receive pins 23 that extend into grooves 24 and by moving the shaft 15 in a lateral direction and opposite to the heretofore mentioned direction, the arms 22' will pass through vertically extending slots in the shoes and engage the slots 18 in the pinions 17 and prevent the pinions from rotating, thus holding the shoes 9 stationary upon the rack bars 7.

In operation the rolls of wire cloth 5 are positioned upon the supporting bars 2 and arranged thereon according to the width of the various rolls of wire cloth. The operator desiring to unwind and measure simultaneously the wire cloth from a certain roll, the handle 21 is pulled in a lateral direction or in the direction of the operator, causing the arms 20 on the collars 19 to engage the slots 18 of the pinions 17 and by turning the crank handle 21 in a desired direction, the pinions will be forced to travel in the direction of the roll of wire cloth which is to be unwound and measured. After the measuring roller 16 and the friction roller 12 are in parallel alinement with the desired roll of wire cloth, the shaft 15 is shoved in a reverse lateral direction causing the arms and the collars 22 to pass through the vertically extending slots of the shoes and engage the slots 18 of the pinions 17 and disengaging the arms 20 of the collars 19 therefrom, thus locking the pinions 17 against rotation and holding the shoes 9 stationary upon the rack bars 7. The end of the wire cloth is threaded between the measuring roller 16 and the friction roller 12 and by rotating the crank handle 21, the measuring roller will rotate and unwind the wire cloth and upon every complete rotation of the measuring roller, a foot of wire cloth will be unwound. The shaft 15 is free to rotate within the shoes 9, pinions 17 and the col-

lars 22, as the pins 23 engage the grooves 24 permitting free rotation thereof.

A scale of 12 inches is applied to one end of the measuring roller 16, to indicate that upon one complete revolution of the measuring roller 16, a foot of wire cloth has been unwound.

While I have shown and described the preferred embodiment of my invention, it will be understood that minor changes in construction, combination and arrangement of parts may be made without departing from the spirit and scope of the invention as claimed.

Having thus described my invention, so what I claim is:

1. A wire cloth rack comprising feet, a pair of upwardly and inwardly extending supporting bars secured to said feet, cross beams secured to the upper ends of said supporting bars and extending to points beyond, vertically extending rack bars secured to the feet and to the ends of the cross beam, said supporting bars provided with upwardly directed notches, spindles journaled in said notches for supporting rolls of wire cloth, shoes slidably mounted on the rack bars, a pair of shafts journaled in said shoes, a measuring roller carried by one of said shafts, a friction roller carried by the other shaft and arranged adjacent the measuring roller to receive the end of the wire cloth, means for moving the friction roller and measuring roller in parallel alinement with any one of the rolls of wire cloth, and means for locking the measuring roller and friction roller in parallel alinement with the desired roll of wire cloth, and means for rotating the measuring roller to unwind and measure the wire cloth simultaneously.

2. A wire cloth rack comprising feet, supporting bars secured to said feet for supporting rolls of wire cloth of various widths, vertically extending rack bars secured to said feet, means for securing the ends of the rack bars and the supporting bars together, shoes slidably mounted on the rack bars, a pair of shafts journaled in said shoes, a measuring roller carried by one of said shafts, a friction roller carried by the other shaft, said rollers positioned adjacent each other to receive the end of the wire cloth therebetween, and means for rotating the measuring roller to unwind and measure the wire cloth simultaneously.

3. A wire cloth rack comprising feet, supporting bars secured to said feet for supporting rolls of various widths of wire cloth, vertically extending rack bars secured to the feet, means for securing the ends of the rack bars and supporting bars together, shoes slidably mounted on the rack bars, a shaft journaled in said shoes, pinions journaled on the shaft and within the shoes to travel upon the rack bars, a shaft journaled in the shoes,

a friction roller carried by second mentioned shaft, a measuring roller carried by first mentioned shaft, for receiving the end of the wire cloth, means for rotating first mentioned shaft, means for locking the pinions of first mentioned shaft to cause said pinions to rotate therewith and travel upon the rack bars, and means carried by first mentioned shaft for an engagement with the pinions to lock said pinions against rotation.

4. A wire cloth rack comprising a pair of feet, supporting bars secured to said feet, means for supporting a plurality of wire cloth rolls of various widths thereon, a pair of rack bars secured to said feet, means for securing the ends of the rack bars and the supporting bars together, a pair of shoes slidably mounted upon the rack bars, a shaft journaled in said shoes, a measuring roller carried by said shaft, pinions journaled on said shaft and positioned within the shoes

for an engagement with the rack bars, means for locking the pinions with the shaft, said shaft provided with grooves therein, collars 25 carried by said shaft, pins carried by the collars for an engagement with the grooves for moving the collars laterally with the shaft for an engagement with the pinions and shoes to lock them against rotation, a 30 shaft journaled in said shoes, a friction roller carried by second mentioned shaft for an engagement with the measuring roller to receive the end of the wire cloth between the friction roller and measuring roller, and 35 means for rotating first mentioned shaft to unwind and measure the wire cloth simultaneously.

In testimony whereof I affix my signature in presence of two witnesses.

ANTRUM W. JOHNSON.
